(57) **CLAIM**

The ornamental design for a display device, as shown and described.

DESCRIPTION

FIG. 1 is a perspective view of the display device, according to an embodiment, shown in a contracted state;

FIG. 2 is a front view thereof;
FIG. 3 is a rear view thereof;
FIG. 4 is a left side view thereof, with the right side view being a mirror image;
FIG. 5 is a top view thereof, with the bottom view being a mirror image;
FIG. 6 is a perspective view thereof, shown in an extended state;
FIG. 7 is a front view thereof;
FIG. 8 is a rear view thereof;
FIG. 9 is a left side view thereof, with the right side view being a mirror image;
FIG. 10 is a top view thereof, with the bottom view being a mirror image;
FIG. 11 is a cross-sectional view taken along the line A-A' in FIG. 1, the left and right edges of the display device's screen being asymmetrical and featuring different curvatures at the left and right sides;
FIG. 12 is a front view thereof, shown in a contracted state;
FIG. 13 is a cross-sectional view taken along the line B-B' in FIG. 6; and
FIG. 14 is a front view thereof, shown in an extended state;
FIG. 15 is a perspective view of the display device, according to another embodiment, shown in a contracted state;
FIG. 16 is a front view thereof;
FIG. 17 is a rear view thereof;
FIG. 18 is a left side view thereof, with the right side view being a mirror image;
FIG. 19 is a top view thereof, with the bottom view being a mirror image;
FIG. 20 is a perspective view thereof, shown in an extended state;
FIG. 21 is a front view thereof;
FIG. 22 is a rear view thereof;
FIG. 23 is a left side view thereof, with the right side view being a mirror image;
FIG. 24 is a top view thereof, with the bottom view being a mirror image;
FIG. 25 is a front view thereof, shown in a contracted state, the left and right edges of the display device's screen being symmetrical; and,
FIG. 26 is a front view thereof, shown in an extended state. The broken lines in the drawings depict portions of the display device and environmental subject matter that form

(Continued)

no part of the claimed design. The broken lines shown in the figures that are immediately adjacent to the shaded areas and define unshaded regions represent the bounds of the claim. All other broken lines are directed to environment. The displayed information on the screen in FIGS. 12, 14, 25, and 26 shows an example of the display device in a state of operation.

1 Claim, 26 Drawing Sheets
